UNITED STATES PATENT OFFICE.

GEORGE L. ROCK, OF WAUKESHA, WISCONSIN.

ENGINE-STARTER.

1,315,577.

Specification of Letters Patent. Patented Sept. 9, 1919.

Application filed December 11, 1916. Serial No. 136,159.

To all whom it may concern:

Be it known that I, GEORGE L. ROCK, a citizen of the United States, and residing at Waukesha, in the county of Waukesha and 5 State of Wisconsin, have invented a new and Improved Engine- Starter, of which the following is a specification.

This invention relates to an engine starter and is an improvement on that described in 10 my pending application Serial Number 27478, filed May 12, 1915, upon which Patent No. 1,208,016 was granted Dec. 12, 1916. In each case the starting impulse is obtained from a spring, the latter being automatically 15 maintained in stressed condition by the engine. The invention includes improvements over the previous construction in the following features, among others:—the mechanism whereby the spring is either 20 held or released; the mechanism whereby the stress is transmitted from the externally toothed driving gear connected to the spring to the associated shaft; the mechanism for controlling the re-winding of the spring by 25 the engine; the manually operated winding mechanism. There is also disclosed and claimed means for regulating the tension of the sprocket chain and there is shown an improved clutch which is claimed in 30 my co-pending application Serial Number 136,160, filed Dec. 11, 1916.

In the drawings, Figure 1 is a plan view, parts being broken away, the frame and floor of the vehicle being omitted. Fig. 2 35 is a side view, partly in section, showing the relation of the parts to the frame. Fig. 3 is a front view corresponding to Fig. 1, the chain casing being removed. Fig. 4 is a fragmentary rear view showing the mechanism 40 for manually rewinding the spring. Fig. 5 is a section on the line 5—5 of Fig. 1. Fig. 6 is a section on the line 6—6 of Fig. 5. Fig. 7 is a section through the front end of the spring casing and associated parts. 45 Fig. 8 is a section on the line 8—8 of Fig. 7. Fig. 9 is a plan view of a portion of the brake band, the leather facing being removed. Fig. 10 is a longitudinal section through the rear end of the spring and 50 associated parts. Fig. 11 is a section on the line 11—11 of Fig. 10. Fig. 12 is a front view of the externally toothed gear shown in Fig. 7, together with the dogs carried thereby. Fig. 13 is a section through 55 the gear showing the mounting of the dogs.

In the embodiment shown, 1 indicates a channeled side bar and 2 a front cross bar of a motor vehicle, and mounted on the latter in any suitable manner is one end 5 of an engine casting. The engine shaft appears at 6.

The engine shaft has alined therewith a starting shaft 8 slideable in a bushing 9 carried at the forward end of the engine casting; at the rear end of this shaft is attached, 65 preferably by means of the pin 12 and key 13 (Fig. 6), a clutch member 14 having a conical head 15. At its front end the engine shaft is provided with a clutch member 16 (that may be substituted for and serve 70 the purpose of the ordinary fan pulley) secured thereon by the cross pin 18 and having a tapered guide 19 adapted to receive the conical head of the member 14. Jaws 20 (preferably an odd number spaced substantially 75 equally angularly about the axis of the engine shaft) project forwardly from the member 16. The member 14 is hollow and has alined longitudinal slots 22 (Fig. 6) through which extends a bar key 23 that 80 may swing about a pivot 24 on a sliding block 25 which is thrust toward the engine shaft by a spring 26 contained in the clutch member. Therefore, when the starter shaft is thrust to the rear it immediately assumes 85 a positive driving relation to the engine shaft, regardless of whether both ends of the bar key happen to be alined with the spaces between the jaws or not, for in case one end of the key strikes a jaw, its other 90 end is instantly snapped about the pivot and thrown into the corresponding space. The chattering and wear incident to ordinary jaw clutches is thus avoided.

Rigid with the forward end of the starting shaft is a sprocket wheel 28 having ratchet teeth 29 to allow the safe application of a starting crank (not shown). The sprocket wheel may be joined to a spring winding shaft 30 parallel to the starting 95 shaft by a chain 31 and sprocket wheel 32, and both wheels and chain may be inclosed by a casing 33 having an opening in alignment with the starter shaft, said opening having a suitable closure 34. The shaft 30 100 is preferably mounted in spaced roller bearings 36 (Fig. 7) carried by a sleeve 38 which projects into and, in effect, forms a part of a head 39 for a spring casing, said head being joined to the barrel 40 of the 105 110

casing by means of the bolts 42 and a flange 43 riveted to said barrel at 44. The sleeve 38 (Fig. 2) passes through and is rotatable in a collar 46 (not shown in Fig. 5 7) which, by means of a pivot 48, is supported by a bracket 49 near the front end of the side bar 1; the collar also has rigid therewith an arm 50 (Figs. 1 and 3) that extends toward the center of the car and 10 has its end threaded to receive a bolt 51 arranged to bear against the lower surface of the cross bar 2. The bolt upon being projected against the cross bar forces the collar 46 to swing counterclockwise (Fig. 3) 15 about the pivot 48, and thereby determines the tension on the chain 31.

The shaft 30 (Fig. 7) has integral therewith a crank 53 that extends into the barrel 40 and has mounted thereon an externally 20 toothed gear 54, a roller bearing 55 preferably being interposed and the rear end of the gear-hub being closed by the diaphragm 56 that abuts a retaining flange 58. The gear 54 is perforated to receive the forwardly turned end 59 of the helical spring or motor 60 that at its rear end 61 is operatively connected to the ratchet gear 62 through mechanism which will be explained later. Any tendency of the ratchet gear to 25 turn counterclockwise (Fig. 3) or clockwise (Fig. 11) is overcome by the spring pressed dog 63 carried in a hollow boss on the supporting bracket 64 for the rear end of the spring and associated parts; therefore when 30 the spring 60 is wound, its full force is thrown upon the gear 54 and tends to rotate the latter in clockwise direction (Fig. 3). Upon the front face of the gear 54 are a plurality of dogs 65 having shanks 66 (Fig. 35 40 13) received in perforations that extend through the gear; the tails 68 of the dogs receive the ends 69 of coil springs 70 that are for the most part housed in perforations in the gear and have their other ends 71 passed through slots in the shanks 66 to 45 form cotters. The tendency of the springs is to turn the dogs clockwise (Fig. 12) whereby they are maintained in engagement with the teeth of a ratchet wheel 72 preferably formed integral with the shaft 30 and crank 53 and co-axial with the latter. When the spring 60 is wound and the gear 54 is released, the shaft 30 is thus turned clockwise, Fig. 3. For the purpose of preventing 50 55 the spring 60 from being thrust against the dogs, pin 73 (Fig. 7) may be inserted in the face of the gear.

The gear 54 is in mesh with the internally toothed gear 75 housed in the head 39; at 60 its forward end the gear 75 is provided with teeth 76 that are received in sockets 78 (Fig. 8) in a brake band which is also housed in the head and includes a steel insert 79 having corrugations (Fig. 9) that preferably 65 extend at an angle to the circumference

thereof, together with the inner and outer facings 80, preferably of chrome tanned leather. A brake expander in the form of a metal band 81 provided with enlarged spaced ends 82 is preferably employed, said 70 ends being thrust apart by the cam 83, the shaft 84 of which projects through the front end of the head and is pinned at 85 to the brake lever 86 (Figs. 3 and 7). The brake band 79-80 is much more certain in its action than ordinary bands and is subject to less wear, seemingly because the alternately thicker and thinner portions of leather have different densities under pressure and possibly also on account of a difference in resiliency in adjacent portions of the insert 79- 80 at any rate, the leather grips more gradually as pressure is applied and is less apt to harden than ordinary bands.

Referring now to the means whereby the 85 spring 60 is rewound:—The clutch member 14 (Fig. 1) is subjected to the stress of a spring 90 that surrounds the starter shaft and is thrust thereby toward the member 16, but is normally held away from the latter by 90 a lever which includes the three arms 91, 92 and 93 and is pivoted on a stud 94 on the engine casing 95. The end of the arm 91, when swung counterclockwise (Fig. 3), lies in the path of a circumferential cam 96 on 95 the clutch member 14 and with the first turn of the engine shaft thereafter disengages the member 14 from the member 16, after which the arm passes down behind the tapered surface 98 (Fig. 6) and retains the 100 parts out of engagement. When the spring 60 is wound and the brake 79-80 is expanded, the tension of the spring is transferred to the housing, which it will be remembered is free to rotate in bearing 46, and causes the 105 latter to carry a torque arm 99 (bolted thereto at 42 and pivotally joined to the arm 92 by a link 101), with it in a clockwise direction (Fig. 3), thereby holding the arm 91 down against the surface 98. This tendency 110 may be overcome and the arm 91 may be withdrawn from the path of the cam 96 (after which the clutch member 14 immediately snaps into engagement with the member 16) manually by means of a suitable connection such as the link 105 (Fig. 1), bell crank 106, link 108 and pedal 109 within convenient reach of the driver's seat. The pivot 110 whereby the link 105 is joined to the arm 93 projects forwardly through a 115 slot 111 in a brake-rod 112, said slot having an inclined end 113, and said brake-rod passing through the side bar 1 and being pivoted to the brake lever 86 by a pin and slot connection. Seated within the side bar is a 120 coiled spring 115, one end 116 of which bears against the web of the side bar whereas the other end 118 is looped around the brake-rod and engages a collar 119 adjustably fixed thereon. The spring tends 125 130

to force the rod to the left (Fig. 3) and normally holds the brake set, but a continued push on the pedal, after the pivot 110 reaches the end of the slot 111—113 (at 5 which point it is retained by a spring 121 that joins the end of the brake rod and a point on the three armed lever near the pivot 94, overcomes the force of the spring 115 and liberates the internally toothed gear 75 10 and associated members, whereupon the shaft 30 is spun clockwise (Fig. 3) by means of the dogs 65 and ratchet teeth 72 to start the engine. The latter then drives the shaft in the same direction and, through 15 the crank 53 (when the brake is set), causes the externally toothed gear to rotate in the internally toothed gear 75 in a direction opposite to the rotation of the shaft 30 and at a much reduced rate, thereby winding the 20 spring 60. When the latter has become sufficiently tensioned, the increasing tendency to swing the torque arm 99 clockwise (Fig. 3) overcomes the pull of the spring 121 and the friction of the pin 110 (that may carry 25 a roller, not shown) in the inclined end 113 of the slot 111, whereupon the three armed lever is thrown to the limit of its movement in a counter-clockwise direction, thus bringing the arm 91 in the path of the cam 96 to 30 disengage the clutch elements as heretofore stated.

The manner of mounting the rear end of the spring 60 and of rewinding the latter manually will now be described (Figs. 10 and 11):—The bracket 64 which is bolted to the side bar forms a cylindrical cap with a perforated extension 125 that, together with a diaphragm 126, forms the support for the ratchet gear 62. Forwardly of the dia- 35 phragm the shaft 128 of the ratchet gear supports the end plate 129 of the spring casing; the casing 40 is rigid with the end plate 129 and together they turn on the shaft 128, being loosely fitted in the housing 64. 40 Still farther forwardly the shaft 128 is squared at 131 and receives the centering and driving member 132 into which the end 61 of the spring 60 projects. The centering member also receives the rear end of an in- 45 inner barrel 133 for the spring 60, the forward end of the inner barrel inclosing and being supported upon the hub of the externally toothed gear 54 (Fig. 7)—this mounting allows the gear 62 to rotate in re- 50 spect to the end of the winding tube or barrel 133, if necessary, and also allows these members to turn together about the axis of the shaft 30.

In order to wind the spring manually 55 from the driver's seat, the following mechanism may be employed (Figs. 1, 2, 4, 10 and 11):—135 indicates the brake lever rigid with the brake shaft 136 (mounted in suitable bearings, not shown) and connected to 60 the usual brake rod 139; this lever extends

up through a slot 140 in the floor 141 of the car and may ordinarily be swung for some distance without affecting the brake. A forwardly projecting arm 142 rigid with the shaft 136 is connected by means of a link 70 143 (Fig. 4) to an arm 144 of a clutch member 145 (Fig. 10) rotatable and slidable in the bearing 125. The teeth of the clutch member engage with teeth 148 on the hub of the ratchet gear 62 but are normally held 75 out of contact therewith by a compression spring 149 pocketed in said clutch member and hub, consequently the normal operation of the brake member does not affect the gear 62. A push-rod 150 having a head project- 80 ing above the floor and its lower end connected to one arm 151 of a bell crank (pivoted to the frame at 153) the other arm 154 of which is arranged to engage the end of the clutch member 145, constitutes means for 85 forcing the latter into engagement with the teeth 148 at will. In order to cushion the rod 150, it may slide through a perforation in the arm 151 and be surrounded by a spring 155 that bears against a collar 156 90 fixed on the rod.

The operation of the entire device will, it is believed, be readily understood from the foregoing. The details of construction may be varied to a considerable extent from that 95 shown, and I do not, therefore, wish to be limited except as indicated by the subjoined claims.

I claim:

1. A starter for internal combustion en- 100 gines comprising a stressed spring arranged to be stressed by being wound about an axis, means for utilizing the stress of the spring to start the engine, a casing for the spring, pivot means for supporting the casing, the 105 axis of said pivot means being out of alignment with the axis about which the spring is wound, a bearing carried by the pivot means, said spring tending to cause the casing to turn in the bearing, means for causing the engine to renew the stress in the spring, and means controlled by the casing in its pivotal movement for disconnecting the engine from the spring. 110

2. A starter for internal combustion en- 115 gines comprising a starter shaft in alinement with the engine shaft, clutch means for connecting the starter shaft to the engine shaft, a motor connected to the starter shaft to drive the latter, a casing for the motor, a 120 support for the casing and in respect to which the casing is movable by the stress in the spring, and means controlled by the movement of said casing relatively to the support for disengaging the clutch means to 125 disconnect the starter shaft from the engine shaft.

3. A starter for internal combustion en- 130 gines comprising a stressed spring, a brake for the spring, a brake rod for the brake, re-

silient means for normally holding the brake set, means for driving the engine shaft from the spring, said means including a clutch, means for normally holding one member of 5 the clutch out of engagement with the other, manually actuated means for moving the clutch holding means to first allow engagement of the clutch members with each other and to thereafter release the brake, means 10 associated with said brake rod for retaining the clutch holding means in the position in which the clutch members are free to become engaged.

4. A starter for internal combustion engines comprising a stressed spring, a shaft driven by said spring, a swingable support for said shaft, a starter shaft parallel to the first mentioned shaft, an endless member whereby the starter shaft is driven from the 20 first mentioned shaft, means for driving the engine from the starter shaft, and means for swinging the shaft support to determine the tension in the endless member.

5. In combination with a motor vehicle 25 including a pair of side bars, a front cross bar, and an engine having its shaft substantially between the side bars, a starter shaft aligned with the engine shaft, a helical spring located substantially parallel to and 30 supported by one of the side bars, a shaft substantially co-axial with the spring and driven thereby, a chain and sprocket gears whereby the last mentioned shaft and the starter shaft are connected, and means associated with the front cross bar for regulating the tension of the chain.

6. A starter for internal combustion engines comprising a spring, means for utilizing the spring to start the engine, a casing 40 for the spring, said casing being movable by an increasing stress in said spring, and means controlled by the movement of the casing for disconnecting the spring from the engine, said last mentioned means including a clutch, resilient means urging an element of the clutch into driving relation to another element thereof, a movable member arranged, when in one position, to withdraw the first mentioned clutch element from 45 driving relation to the last mentioned element, and another movable member for controlling the first mentioned movable member, one of the movable members being slotted and the other having means that projects into the slot, and a spring tending to 50 urge one of the movable members toward the other.

7. A starter for internal combustion engines comprising a spring arranged to be 60 stressed by being wound about its own axis, means for utilizing the stress of the spring for starting the engine, means for causing the engine to wind the spring to renew the stress therein, said last mentioned means including a shaft, a crank for the shaft, an

externally toothed gear in which the crank turns, an internally toothed gear surrounding and in mesh with the externally toothed gear, means for normally preventing one of the gears from turning, the other gear 70 being arranged to transmit movement to the spring, whereby the last mentioned gear is driven from the shaft at a reduced speed to wind the spring, and a movable dog carried by the last mentioned gear for driving 75 the shaft from the spring.

8. A starter for internal combustion engines comprising a spring arranged to be stressed by being wound about its own axis, 80 means for utilizing the stress of the spring for starting the engine, means for causing the engine to wind the spring to renew the stress therein, said last mentioned means including a shaft, a crank for the shaft, an externally toothed gear in which the crank turns, an internally toothed gear surrounding and in mesh with the externally toothed gear, means for normally preventing the internally toothed gear from turning, the externally toothed gear being arranged to 90 transmit movement to the spring, whereby the externally toothed gear is driven from the shaft at a reduced speed to wind the spring, ratchet teeth rigid with the shaft, and a dog carried by said externally toothed 95 gear for driving the shaft from the spring.

9. In a starter for internal combustion engines, a coiled spring, means for transmitting stress to and from said spring comprising a shaft, a crank rigid therewith, an 100 externally toothed gear rotatable on the crank, an internally toothed gear in mesh with the externally toothed gear, a friction brake for controlling the internally toothed gear, teeth rigid with the shaft, and a movable dog carried by one of the gears and arranged to engage said teeth.

10. In a starter for internal combustion engines, a coiled spring, means for transmitting stress to and from said spring comprising a combined shaft, ratchet gear and crank, an externally toothed gear rotatable on the crank, an internally toothed gear in mesh with the externally toothed gear, a friction brake for controlling the internally 115 toothed gear, and a plurality of movable dogs carried by said externally toothed gear for engagement with the ratchet gear.

11. In a starter for the engine of a motor vehicle, a coiled spring, a casing for said spring, pivot means for supporting one end of said spring in such manner that the spring may swing in planes including its own axis, means for utilizing the stress in said spring to start the engine, and engine 120 driven means for renewing the stress in the spring.

12. In a starter for internal combustion engines, a coiled spring, means for winding said spring comprising a shaft, a crank 130

rigid therewith, an externally toothed gear rotatable on the crank, an internally toothed gear in mesh with the externally toothed gear, a friction brake for controlling the 5 externally toothed gear, said brake including a corrugated metal band and a flexible facing therefor.

13. In a starter for internal combustion engines, a coiled spring, means for winding 10 said spring comprising a shaft, a crank rigid therewith, an externally toothed gear rotatable on the crank, an internally toothed gear in mesh with the externally toothed gear, a friction brake for controlling the externally toothed gear, said brake including 15 a corrugated annular metal band, a leather facing therefor, a seat with which the facing is arranged to engage, and means for expanding the band.
- 20 14. In a starter for internal combustion engines, a coiled spring, means for winding said spring comprising a shaft, a crank rigid therewith, an externally toothed gear rotatable on the crank, an internally toothed 25 gear in mesh with the externally toothed gear, a friction brake for controlling the externally toothed gear, said brake including an annular corrugated metal insert, tough flexible annular facings for the insert, a seat 30 with which one of the facings is arranged to engage, and means arranged to engage with the other facing for forcing the first named facing into tight engagement with the seat.
15. In a starter for internal combustion 35 engines, a coiled spring, means connected to one end of the spring for starting an engine, and manually operable means connected to the other end of the spring for winding said spring, said last mentioned 40 means comprising a ratchet wheel, a dog for preventing the wheel from turning in one direction, and a clutch the elements of which are normally disconnected from each

other through which said ratchet wheel may be driven in the opposite direction. 45

16. In a starter for internal combustion engines, a coiled spring, means connected to one end of the spring for starting an engine, and manually operable means connected to the other end of the spring for 50 winding said spring, said last mentioned means comprising a ratchet wheel, a dog for preventing the wheel from turning in one direction, and a clutch member 55 slidably longitudinally of the axis of the coiled spring, said ratchet wheel having rigid therewith teeth with which the clutch member engages when in one position whereby the ratchet wheel may be driven in the opposite direction. 60

17. In a starter for internal combustion engines of motor vehicles, a spring, means connected to the spring for starting the engine, manually operable means for renewing the stress in said spring, said last mentioned 65 means including an actuating lever, a clutch through which force from said lever is transmitted to said spring, and a clutch-operating lever, both of said levers being within reach of a driver on the seat of the vehicle. 70

18. In a starter for internal combustion engines of motor vehicles, a spring, means connected to the spring for starting the engine, manually operable means for renewing the stress in said spring, said last mentioned 75 means including an actuating lever, a clutch through which force from said lever is transmitted to said spring, said clutch including a slidable element and a non-slidable element, a spring for normally holding the slidable element out of engagement with the other element, and a lever whereby said slidable element may be moved into engagement with the other element. 80

GEORGE L. ROCK.
